P. FRANTZ

DOOR LATCH

Filed Sept. 5, 1922

Inventor:
Peter Frantz.
by Arthur H. Durand, Atty.

Patented Dec. 22, 1925.

UNITED STATES PATENT OFFICE.

PETER FRANTZ, OF STERLING, ILLINOIS, ASSIGNOR TO FRANTZ MANUFACTURING COMPANY, OF STERLING, ILLINOIS, A CORPORATION OF ILLINOIS.

DOOR LATCH.

Application filed September 5, 1922. Serial No. 586,129.

To all whom it may concern:

Be it known that I, PETER FRANTZ, a citizen of the United States, and resident of Sterling, Whiteside County, Illinois, have **5** invented a certain new and useful Improvement in Door Latches, of which the following is a specification.

This invention relates to latches or locking devices for doors or windows or other **10** things of a similar nature.

Generally stated, the object of the invention is to provide a novel and improved construction whereby a reciprocating locking bolt, or other suitable locking device or **15** latch, is operatively connected to a handle by which the door or window is opened and closed, or to a point adjacent said handle, so that the bolt or other locking device may be operated by the same hand which will **20** grasp the handle.

Another object is to provide an improved construction and arrangement whereby a door or window is provided with a handle for opening and closing the door or window, **25** in combination with a locking bolt or latching device located at a point remote therefrom, and with means adjacent said handle to control the said locking bolt or latching device, so that the latter may be operated **30** by the same hand which must grasp the handle in opening and closing the door or window.

It is also an object to provide certain details and features of construction tending to **35** increase the general efficiency and the desirability of a door or window handle and locking device controlling means of this particular character.

To the foregoing and other useful ends the **40** invention consists in matters hereinafter set forth and claimed and shown in the accompanying drawings in which—

Figure 1 is a front elevation of a door provided with locking means embodying the **45** principles of the invention.

Figure 2 is an enlarged front elevation of the locking means shown in Figure 1, with certain portions thereof shown broken away for convenience of illustration.

Figure 3 is a vertical section on line 3—3 **50** in Figure 2.

Figure 4 is a horizontal section on line 4—4 in Figure 2.

Figure 5 is a plan view of the thumb-piece of the chain pull by which the locking **55** device is controlled.

As thus illustrated, the invention comprises a handle or grip 1 secured by screws 2 at the upper and lower ends thereof to the door 3 in position to be grasped by the **60** hand in opening and closing the door. The upper portion of this handle is bent outwardly at 4 and is provided with a slot 5 therein, and the thumb-piece 6 is inserted outwardly through this slot, the transverse **65** rear end portion 7 of this thumb-piece holding the latter in place and forming a sort of pivot therefor. A sheet metal bolt housing 8 is secured to the door at the upper edge thereof, by screws 9, and this housing **70** contains a tubular bolt 10 to which is connected a flat strip 11 which extends downwardly in the opening 12 in the lower end of the housing. A coil spring 13 is interposed between the lower end of the locking **75** bolt and the bottom of the housing, so that this spring is compressed when the bolt is pulled downward. For this purpose a chain **80**

14 connects the lower end of the strip 11 with the thumb-piece 6 previously mentioned, whereby this thumb-piece is held normally in raised position by said spring. The upper end of said locking bolt is rounded at **85** 15, and when the door is closed this rounded portion strikes the sheet metal strike piece 16 which is secured to the door frame at a point above the door by the screws 18 in position to receive the projecting upper end portion of the bolt when the door is fully closed. When it is desired to open the door, the handle 1 is grasped and the thumb of the same hand is placed on the thumb-piece **90** 6 and pressure on the latter in a downward direction will cause the chain 14 to pull on the strips 11 and thereby pull the bolt 10 downward out of the strike piece 16 previously mentioned.

From the foregoing it will be seen that

means are associated with a handle to control a bolt or locking device, so that the locking device is under control of the hand which must grasp the handle, and the arrangement is such that the locking device may be located at a point remote from the handle. It is obvious, of course, that the different elements can be arranged in any suitable or desired manner, depending upon the character of the door or window or other closure to which the devices are applied.

It will be seen that the handle member 1 is separately mounted and is adapted to be placed at any desired distance from the locking bolt, so that the door may be of any desired size or height, and the chain 14 will be of any suitable length, depending upon the distance between the handle and the locking bolt. The thumb-piece 6, however, is disposed immediately over the handle grip, being carried by the handle member, and is operable by the thumb in the natural position of the hand while the handle grip is actually in the grasp of such hand.

It will be seen that the screws 2 serve as means for rigidly securing the handle member 1 to the door or other closure, so that this handle does not constitute any means whatever for operating the latch or locking device. To the contrary, the thumb-piece 6 constitutes the sole means for manually operating the lock or latch, through the medium of the chain 14 or other depending connection. Furthermore, the thumb-piece 6, by reason of the spring 13 or other suitable means, is held normally in raised position above the rigid handle. Therefore, of course, the door automatically latches when it closes, as shown and described.

What I claim as my invention is—

1. In locking means for a door or window or other closure, the combination of a handle member having a hand grip, means whereby said member is rigidly secured to said closure, a reciprocating locking bolt mounted on said closure a distance from and independently of said handle, depending upon the size of the door and the consequent distance between the convenient position for the handle and the effective position for the locking bolt, means to be engaged by said bolt to lock the closure in closed position, and a connection extending the distance from said locking bolt to a point of control adjacent said handle member, so that said locking bolt is controllable by the thumb of the hand in the act of grasping the handle to open the door.

2. A structure as specified in claim 1, said closure being a door, and said means for engaging the locking bolt being mounted on the door frame above the door, and said handle being disposed some distance below said locking bolt.

3. A structure as specified in claim 1, said

connection comprising a thumb-piece disposed immediately above the handle grip and carried by said member and means extending upward from said thumb-piece to said locking bolt, and whereby downward movement of said thumb-piece serves to unlock the door formed by said closure.

4. A structure as specified in claim 1, said handle member having an outwardly bent upper portion formed with a slot therein, 75 said connection comprising a thumb-piece inserted outwardly through said slot, with means on the inner end of said thumb-piece to hold it in place and form a pivotal axis about which the outer end of the thumb-piece is movable up and down above the handle grip.

5. In locking means for doors or windows or the like, the combination of a handle member having a hand grip for opening 85 and closing the door or window or other closure, adapted to be grasped with the thumb uppermost, when the locking means are installed vertically, locking means therefor, a thumb-piece immediately above 90 the handle grip, means whereby the thumb-piece is mounted to move up and down, adapted to be depressed by pressure of the thumb downward toward the upper portion of said handle, and a connection between 95 said thumb-piece and said locking means, there being spring means to keep said thumb-piece normally raised above the handle.

6. In locking means for a door or window 100 or other closure, the combination of a handle member having a grip and secured to the closure, a reciprocating locking bolt mounted on said closure, means to be engaged by said bolt to lock the closure in closed position, and a connection extending from said locking bolt to a point adjacent said handle member, whereby said locking bolt is controllable by the same hand which must grasp said handle to open the door, said connection comprising a thumb-piece disposed immediately above the handle grip and carried by 105 said member and means extending upward from said thumb-piece to said locking bolt, and whereby downward movement of said thumb-piece serves to unlock the door 110 formed by said closure.

7. In locking means for a door or window or other closure, the combination of a handle member having a grip and secured to the 120 closure, a reciprocating locking bolt mounted on said closure, means to be engaged by said bolt to lock the closure in closed position, and a connection extending from said locking bolt to a point adjacent said handle member, whereby said locking bolt is controllable by the same hand which must grasp 125 said handle to open the door, said handle member having an outwardly bent upper portion formed with a slot therein, said con- 130

nection including a thumb-piece inserted outwardly through said slot, with means on the inner end of said thumb-piece to hold it in place and form a pivotal axis about which the outer end of the thumb-piece is movable up and down above the handle grip.

8. A structure as specified in claim 1, including provisions whereby the locking means automatically latches when the clo-

sure is moved into closed position, serving to 10 normally hold said connection in operable position.

9. A structure as specified in claim 5, said locking means having provisions for automatically latching the door when in closed 15 position, serving to normally maintain said thumb-piece in operable position.

PETER FRANTZ.
